UNITED STATES PATENT OFFICE.

AUGUST WILLHELM ULLBERG, OF PHILADELPHIA, PENNSYLVANIA, AS-SIGNOR TO THE PHILADELPHIA HARDWARE AND MALLEABLE IRON WORKS, OF SAME PLACE.

DESIGN FOR A REGISTER-PLATE.

SPECIFICATION forming part of Design No. 34,348, dated April 9, 1901.

Application filed March 14, 1901. Serial No. 51,212. Term of patent 7 years.

To all whom it may concern:

Be it known that I, AUGUST WILLHELM ULLBERG, a citizen of the United States, residing in the city and county of Philadelphia, State of Pennsylvania, have invented and produced a new and original Design for Register-Plates, of which the following is a specification, reference being had to the accompanying drawing, forming part thereof.

The leading feature of my design for a register-plate is, first, a central panel composed of a torch, columns flanking the same, and an arch on said column, next an inner border for said panel composed of side scrolls and corner-crosses, and next an exterior border composed of scrolls and leaves.

The drawing represents a face view of a register-front embodying my design.

In the drawing, A designates a register-

plate consisting of the central panel B, the inner border C, and the exterior border D. The central panel is composed of the torch E, the side columns F, and the arch G. The columns rest on the paneled base H, and the torch is flanked by the scrolls J. The border C is composed of the scrolls K and corner-crosses L. The border D is composed of the scrolls M and leaves N.

Having thus described my invention, what I claim as new, and desire to secure by Letters Patent, is—

The design for a register-plate substantially as shown and described.

AUGUST WILLHELM ULLBERG.
